UNITED STATES PATENT OFFICE.

CHARLES W. AHRENS, OF NEW YORK, N. Y.

COLLAR-SUPPORTER.

1,337,989.

Specification of Letters Patent. Patented Apr. 27, 1920.

Application filed May 21, 1919. Serial No. 298,743.

To all whom it may concern:

Be it known that I, CHARLES W. AHRENS, a citizen of the United States of America, residing at New York, N. Y., have invented 5 a new and useful Collar-Supporter, of which the following is a specification.

The objects of my invention are to provide a supporter for so-called "soft" collars, which will be light, simple and inexpensive, which can be easily applied and which will support the collar in proper shape without discomfort to the wearer. 10

Briefly, the invention consists in a preferred form of a wire frame made with upright posts which are connected at their lower ends with a collar button engaging portion and which are provided at their upper ends with laterally extending collar supporting arms, the free ends of said arms 20 being preferably supported by braces which connect with the lower ends of the uprights and carry hooks for engagement with the flaps of the collar.

Other features will appear as the specification proceeds and will be understood from consideration of the accompanying drawing wherein I have illustrated a practical embodiment of the invention, this with the understanding, however, that changes 30 and modifications may be made without departure from the scope of the invention as set forth in the appended claims.

In said drawing:—

Figure 1 is a front elevation showing the 35 invention in use in connection with a soft collar of the "turned-down" type.

Fig. 2 is a detached perspective view of the supporter.

Fig. 3 is a broken detail view of a slight 40 modification.

The supporter consists of a light spring frame made of suitable wire such as nickel silver and bent to provide upright posts 3, 4, the lateral collar supporting arms 5, 6, 45 and the angularly extending braces 7.

The upright posts 3, 4, are connected in spaced relation at their lower ends by a base portion which is adapted to be supported adjacent the collar button of the 50 shirt and may be bent to form a collar button inclosing loop 8. Above this collar button engaging loop the upright posts are bent angularly as indicated at 9 and these angularly bent portions overlap or cross 55 one another as shown in Fig. 2. These crossed portions are preferably connected to-

gether as by means of an inclosing collar 10 which serves to secure these intermediate portions of the posts together and further serves to hold the upper ends of the posts in proper spaced relation.

The collar supporting arms 5 and 6 extend laterally in opposite directions from the upper ends of the posts 3, 4, and fit within the fold at the upper edge of the collar so as to support said upper edge of the collar for an appreciable distance at each side of the center of the collar. 65

The braces 7 are bent down at an angle from the free outer ends of the collar supporting arms 5, 6, and are preferably slidably connected with the lower end portions of the upright posts 3, 4, as by looping them thereabout as indicated at 11. These braces tend thereby to support the free outer 75 ends of the collar engaging arms, but at the same time permit said arms to yield in a downward direction in accordance with the movements of the neck.

The ends of the collar braces are shown 80 bent into reversely extending sharp pointed hooks 12 with which are engaged the adjacent flaps of the collar.

In use, after the collar is applied to the shirt, the supporter is slipped up under the 85 fold of the collar and hooked over the collar button. After the tie is fastened the flaps of the collar are then drawn together to the extent desired and caught over the pointed hooks at the lower ends of the upright 90 posts. The collar is thus properly supported at its upper edge and the flaps of the collar are caught down so that they will not become wrinkled and will not stand out.

The device, it will be seen, is simple and 95 inexpensive, can be easily applied and holds the collar in proper shape.

In the form of the invention illustrated in Fig. 3, the post members 3 and 4 are not crossed as in the construction described, 100 but are in the form of plain uprights held in spaced relation by a transverse strut or strap 14 which is shown as made of flat sheet metal having end portions partially wrapped about the upright posts. This construction has all the advantages of the first 105 construction and is somewhat easier to make.

Another advantage of my invention is that the supporting frame may be used as a 110 mounting for a scarf or necktie, the tie being simply fastened, for instance, with the

usual "fourinhand knot" to the upright posts 3—4 as indicated in Fig. 2, and the device being then used as before by attaching it to the collar button and hooking the 5 collar flaps down over the hooks 12.

I claim:—

1. A collar supporter comprising, two oppositely disposed independently flexible upper collar supporting arms spaced apart at 10 the center, a base member adapted to engage a support, means for connecting the base member and the inner ends of the upper arms and side braces connecting the base member with the outer ends of the upper 15 arms.
2. A collar supporter comprising, two oppositely disposed independently flexible upper collar supporting arms spaced apart at the center, a base member adapted to engage 20 a support, means for connecting the base member and the inner ends of the upper arms and side braces connecting the base member with the outer ends of the upper arms, said side braces having sliding connections with the base member.
3. In a construction of the character described, the combination for a folded soft collar of a supporting device having horizontal portions for fitting in between the 30 folds of the collar on opposite sides of the front and spaced apart from each other at the center, a connecting member below the level of the horizontal portions, side arms connected to the outer ends of the horizontal 35 portions and having means at their lower ends for engaging the points of the collar to hold the same, means for supporting said device at the front of the collar adjacent the collar button and vertically disposed 40 means extending from said supporting means adjacent the collar button to said connecting member.
4. In a construction of the character described for supporting the front of a folded soft collar, a supporting device, comprising a base portion adapted to be supported adjacent the collar button hole, upper horizontal portions for fitting in between the folds of the collar on opposite 45 sides of the front, means of connection between said base portion and the inner ends of the upper portions, resilient lateral braces connected to the outer ends of the upper portions and having vertically sliding connections with the base portion and means carried by the braces and vertically movable with the slideable connections thereof for engaging the points of the collar to stretch the same.
5. A collar supporter, comprising spaced upright posts connected at their lower ends and provided therewith a base portion, the upper ends of said upright posts being disposed in spaced relation, lateral collar 55 supporting arms extending in opposite directions from said upper ends of the upright posts and braces extending from the free ends of said lateral supporting arms to the lower portions of the upright posts, said braces terminating at their lower ends in reversely bent pointed hooks for engagement with the adjacent flaps of a collar. 70
6. A collar supporter made of spring wire and comprising spaced upright posts connected at their lower ends by a base portion and having reversely bent portions crossing above said base portion, lateral collar supporting arms extending in opposite directions from the upper ends of said upright posts and reversely disposed sharp pointed hooks at the lower ends of said upright posts for engagement with the adjoining flaps of a collar. 75
7. A collar supporter made of spring wire and comprising upright posts connected at their lower ends by a base portion and having angularly bent portions crossing above said base portion, lateral supporting arms extending in opposite directions from the upper ends of the upright posts, braces 80 extending from the outer free ends of the supporting arms to the lower ends of the upright posts and provided at such points with loops slidably engaging the lower end portions of the upright posts and reversely bent hooks at the ends of said braces for engagement with the adjacent flaps of a collar. 85
8. A collar supporter comprising spaced upright portions provided with positioning means at their lower ends, collar supporting portions extending laterally in opposite directions from the upper ends of said upright portions, angular braces extending from the outer ends of said collar supporting portions to the lower ends of the upright portions, and hooks at the lower ends of said angular braces for engagement by the adjacent folds of a collar. 90
9. A wire collar supporter comprising spaced upright posts connected at their lower ends and provided at their upper ends with reversely extending lateral collar supporting portions and means holding the intermediate portions of the upright posts in spaced relation at a point above the connected lower ends thereof and below the upper spaced ends. 100
10. A collar supporter comprising, two independently flexible oppositely disposed collar supporting frames spaced apart from each other at the upper central portion of the device, a base member connected to the said frames near the center and having a sliding connection with the lower ends of the sides of the frames. 110
11. A collar supporter comprising, two upper collar supporting arms spaced apart from each other at the center of the collar, a base member connected to the inner ends 115
- 65 supporting arms extending in opposite directions from said upper ends of the upright posts and braces extending from the free ends of said lateral supporting arms to the lower portions of the upright posts, said braces terminating at their lower ends in reversely bent pointed hooks for engagement with the adjacent flaps of a collar. 120
- 65 supporting arms extending in opposite directions from said upper ends of the upright posts and braces extending from the free ends of said lateral supporting arms to the lower portions of the upright posts, said braces terminating at their lower ends in reversely bent pointed hooks for engagement with the adjacent flaps of a collar. 125
- 65 supporting arms extending in opposite directions from said upper ends of the upright posts and braces extending from the free ends of said lateral supporting arms to the lower portions of the upright posts, said braces terminating at their lower ends in reversely bent pointed hooks for engagement with the adjacent flaps of a collar. 130

of said arms on opposite sides of the center, and side braces connected to the outer ends of the arms and having sliding connections with the base member to permit independent yielding of the two arms.

12. A collar supporter comprising, two upper collar supporting arms spaced apart from each other at the center of the collar, a base member connected to the inner ends

of said arms on opposite sides of the center, and side braces connected to the outer ends of the arms and having sliding connections with the base member to permit independent yielding of the two arms, said side members having collar engaging means adjacent said base member.

CHARLES W. AHRENS.
